UNITED STATES PATENT OFFICE.

CLIFTON E. WERTS AND WALTER G. WERTS, OF RUSSELL, IOWA.

EARTH-HANDLING MACHINE.

1,296,347.

Specification of Letters Patent.

Patented Mar. 4, 1919.

Application filed January 31, 1918. Serial No. 214,774.

To all whom it may concern:

Be it known that we, CLIFTON E. WERTS and WALTER G. WERTS, citizens of the United States, and residents of Russell, in the county of Lucas and State of Iowa, have invented a certain new and useful Earth-Handling Machine, of which the following is a specification.

Our invention relates to machines for handling earth for grading roads, filling holes, ditches and the like and cutting off hills or banks.

The object of our invention is to provide an earth handling machine having a sheave wheel and designed to be operated by means of a cable suitably anchored and wound on said wheel, which machine is provided with a prime mover such, for instance, as a gasoline engine for operating said sheave wheel.

Still a further object is to provide such a machine having an endless conveyer preferably mounted comparatively low on the frame of the machine and operatively connected with said prime mover for being moved in either direction, whereby said endless conveyer may be discharged at either end.

Still a further object is to provide such a means having a frame and supporting wheels, and having such an endless conveyer, and having a suitable frame arranged with one end near the supporting wheels at one end of the machine so as to permit the discharge of a load at such end of the machine for filling a ditch or the like.

Still a further object is to provide such a machine having such an endless conveyer, and having spaced from one end thereof an adjustable scraper blade.

Still a further object is to provide such a machine having such a conveyer, and having adjacent to one end thereof a cutter blade so constructed and arranged as to cut earth when the machine is advanced and to elevate said earth toward the conveyer, which machine has also means for simultaneously raising and lowering said cutter blade and the end of the conveyer adjacent thereto, and has also means for raising the cutter blade independently of the conveyer.

A further object is to provide such mechanism as has just been described in connection with a shield located in spaced position above the end of the conveyer adjacent to the cutter blade, which shield is so mounted as to be operated simultaneously with the

cutter blade and to be raised away from the conveyer when said cutter blade is moved away from the conveyer.

An additional object of our invention is to provide in a machine of the kind mentioned a conveyer of special construction adapted to support a heavy load of dirt, in connection with suitable mechanism for operating said conveyer.

Still a further object is to provide such a machine capable, by slight adjustment, of being propelled over the ground by its own power applied to its supporting wheels.

With these and other objects in view our invention consists in the construction, arrangement, and combination of the various parts of our device, whereby the objects contemplated are attained, as hereinafter more fully set forth, pointed out in our claims, and illustrated in the accompanying drawings, in which:

Figure 1 shows a side elevation of an earth handling machine embodying our invention.

Fig. 2 shows a top or plan view of the same.

Fig. 3 shows an enlarged, detail view of the mechanism at the front end of the machine.

Fig. 4 shows an enlarged, detail view of part of the controlling and operating mechanism.

Fig. 5 is a side elevation of the front portion of the machine taken from the opposite side from that shown in Fig. 1.

Fig. 6 is an enlarged, detail, sectional view of part of the mechanism for operating the grader blade.

Fig. 7 is a detail view illustrating the arrangement of the gears for operating the conveyer.

Fig. 8 is a detail, sectional view taken on the line 8-8 of Fig. 2.

Fig. 9 shows a detail view partly in section illustrating the construction and arrangement of the cable and the springs connected therewith.

The frame of our improved machine comprises a pair of parallel, spaced, horizontal, longitudinally extending frame members, which we have indicated in the accompanying drawings by the reference character 10. Extending forwardly from the frame members 10 are frame members 11 which converge and are connected together at their forward ends. Extending rearwardly from the frame members 10 are

similar frame members 12 which converge and are connected at their rearward ends. The frame members 10, 11 and 12 are preferably made of channel iron.

5 There is provided a suitable number of transverse frame members 13 for connecting and bracing the frame members 10.

Suitably supported on the frame of the machine is a prime mover 14 which may be 10 a gasoline engine.

There is supported on the frame an endless carrier having the spaced side wall frame members 15. Connected with the side wall frame members 15 are brackets 16 which are pivotally supported at 17 on the respective frame members 10 for permitting the tilting of the endless carrier.

Connecting the wall members 15 is a series of shafts 18, having at their ends 20 spindles 19. Mounted on the shafts 18, which form rollers, is an endless conveyer belt 20, shown in Fig. 8.

On the engine shaft 21, shown in Fig. 2, is a fly wheel 22 having formed thereon a 25 clutch member 23.

Suitably mounted on the frame and extending longitudinally thereof, forwardly of the engine in alinement with the engine shaft 21, is a shaft 24. On the rear end 30 of the shaft 24 is slidably but non-rotatably mounted a clutch member 25, illustrated in Figs. 2 and 4. On the shaft 24 is a collar 26 and between the collar 26 and the clutch member 25 is a coil spring 27 which yieldingly presses the clutch member 25 toward the clutch member 23.

Centrally pivoted on the frame of the machine is a bell crank lever 28, one end 40 of which is pivoted to the clutch 25, and the other end of which is pivoted to a link 29. The link 29 is pivoted to a lever 30, whereby the clutch 25 may be moved out of engagement with the clutch member 23.

It will be seen that the operation of the 45 lever 30 for throwing the clutch members, hereinbefore described, out of engagement serves to compress the spring 27.

Slidably but non-rotatably mounted on the shaft 24 is a friction wheel 31. Connected with the hub of the wheel 31 is a 50 collar 32, to which is pivoted a link 33. The link 33 is pivoted to a lever 34. One end of the lever 34 is pivoted to the frame of the machine.

55 Pivoted to the lever 34 between its ends is a link 35 which is in turn pivoted to a lever 36.

Suitably mounted on the machine is a transverse shaft 37, shown in Fig. 4. On 60 the shaft 37 is slidably but non-rotatably mounted a friction disk 38, having a grooved hub 39.

Pivoted to the frame of the machine is 65 a lever 40 having a pin 41, which travels in the groove of the hub 39.

Pivoted to the lever 40 is a link 42 which is in turn pivoted to a lever 43.

On the outer end of the shaft 37 is a sprocket gear 44 on which is a sprocket chain 45.

Suitably mounted on the frame of the machine rearwardly of the shaft 37 is a shaft 46, shown in Fig. 5, on which is a sprocket 47 in line with the sprocket 44. The chain 45 travels on the sprocket 47. 70

On the shaft 46 is a sprocket 48, as shown in Fig. 2. The sprocket 48 is in line with a sprocket 50 on the outer end of one of the spindles 19. A chain 49 travels on the sprockets 48 and 50. The chain 49 is provided with a casing 51. On the spindles 19 are a series of intermeshing gears 52, illustrated in Fig. 7. It will be noted that the alternate gears 52 are fixed to the spindles 19, while the intermediate gears 52 are rotatably mounted thereon, so that every other spindle 19 and roller 18 is power driven. By this construction it is possible to easily move a heavy load of dirt on the endless carrier 20, and there is no danger 80 of the endless belt or carrier 20 of sliding on the rollers 18.

It should be noted that the pivot point 17 of the endless carrier frame is at the center of the shaft 46, so that the chain 45 will be 90 in proper position in all of the tilted positions of the endless carrier.

It will be seen from the foregoing description that by the manipulation of the clutch member 25 the shaft 24 may be thrown 100 into or out of gear. By means of the lever 43 the endless carrier may be thrown into and out of gear by throwing the disk 38 into or out of operative contact with the wheel 31. By means of the lever 36, the wheel 105 31 may be adjusted for operating the disk 38 in different directions for thereby operating the upper stretch of the endless belt 20 in either direction.

Extending upwardly from the opposite 110 side wall members 15, at the forward end of the machine, are frame members 53 on which are toothed rack bars 54 curved on the arcs of circles having their centers at the center of the shaft 46. 115

On the frame of the machine is mounted a transverse shaft 55 on which are gears 56 in mesh with the respective racks 54.

Mounted in suitable uprights 57 on the frame, as shown in Figs. 5 and 8, is a shaft 120 58 on which is fixed a large hand-wheel 59. On the shaft 58 is a small sprocket wheel 60 which is alined with a larger sprocket wheel 61 on the shaft 55. A chain 62 travels on the sprockets 60 and 61. By rotating 125 the hand-wheel 59 the shaft 55 may be rotated for raising and lowering the forward end of the endless carrier through the gears 56, the racks 54 and the frame members 53.

The wheel 59 has a hub 100 on which is 130

5 mounted a brake band 101 which may be suitably operated from a foot pedal 102 for preventing the weight of the load at the forward end of the endless carrier from tilting the forward end of the carrier downwardly when such downward tilting is not desired.

10 The tilting of the endless carrier frame and the endless conveyer belt carried thereon has several functions which will be hereinafter more fully referred to.

15 At the forward end of the endless conveyer is a double cutting scoop or blade device, which for convenience we shall call the earth cutting device, which is shown in Figs. 1, 5 and 8, and comprises a pair of spaced side wall members 63.

20 Connecting the side wall members 63 at the lower edges thereof is a bottom member 64 above which is what may be called an elevating member 65 which is curved from its forward end upwardly and rearwardly when the earth cutting device is in its lowermost position. The earth cutting device has 25 a cutting edge 66 and supports teeth or breakers 66^a the points of which extend forwardly beyond the edge 66.

20 Pivotedly supported on the walls 15 of the conveyer frame at the forward ends thereof and adjacent to the upper ends of the respective members 63 are levers 67, the forward ends of which are secured to the members 63. The rear ends of the levers 67 are pivoted to the lower ends of the links 68. 35 Mounted in the upper ends of the frame members 53 is a transverse shaft 69 on the ends of which are fixed arms 70. The upper ends of the links 68 are pivoted to the arms 70. On the shaft 69 is a worm gear 71, shown in Fig. 8.

40 Suitably mounted in a bracket 72 is a shaft or rod 73 on one end of which is a crank handle 74.

45 Suitably mounted near the worm gear 71 is a shaft 75 on which is a worm 76 in mesh with a worm gear 71. The shaft 75 is connected by means of a universal joint 77 with a shaft 73. The shaft 73 is allowed some play in its bearing in the bracket 72.

50 It will be seen that by manipulating the crank 74 the shafts 73 and 75 will be rotated for rotating the worm 76 and the worm gear 71 for thereby imparting rotation to the shaft 69. The rotation of the shaft 69 moves 55 the arms 70 for raising or lowering the links 68 and the rear ends of the levers 67 for thereby raising or lowering the earth cutting device.

55 It will be seen that the earth cutting device and the shield 80 may be raised or lowered independently of the endless carrier frame, and that the mechanism for raising or lowering the earth digging device is largely mounted on the frame members 53, 60 so that the earth cutting device is also raised

or lowered whenever the forward end of the carrier frame is tilted.

It is important that it should be possible to swing the earth cutting device away from the forward end of the endless carrier at 70 certain times in order that the load of dirt on the endless carrier may be discharged when desired at the forward end of said carrier without interference from the earth cutting device.

75

On the side wall members 15 of the endless carrier frame, near the forward ends thereof, are upwardly extending brackets 78 to which are pivoted forwardly extending arms 79. The arms 79 support between them a 80 flat plate or shield 80, the purpose of which will be hereinafter referred to.

On the shafts 69 are fixed arms 81 to which are pivoted downwardly extending links 82. The links 82 are pivoted at their 85 lower ends to the forward ends of the arms 79, and the parts just described are so arranged that when the shaft 69 is rotated for raising the earth cutting device the plate 80 is simultaneously raised, and when the earth cutting device is lowered the plate 80 is lowered.

At the forward part of the machine are suitably mounted upright shafts 83 which have at their lower ends spindles 84 on 95 which are mounted large wheels 85.

Supported on the rear ends of the frame members 12 is a platform 86. Below the rear ends of the frame members 12 are turn-table members 87 and 88. Extending downwardly from the lower turn-table member 88 are supporting bearing members 89 which carry a shaft 90 on which is mounted a supporting wheel 91. For turning the lower turn-table member 88 there is provided an 100 upright shaft 92 having at its upper end a hand-wheel 93 and at its lower end a beveled gear 94. The beveled gear 94 meshes with a beveled gear 95 on a shaft 96. The shaft 96 carries a worm 97 which meshes with teeth 110 98 on the lower turn-table member 88. It will be seen that by the operation of the hand-wheel 93 the wheel 91 may be turned as desired for steering the rear end of the machine.

115 We preferably arrange our machine so that the wheels at both ends are steerable and for steering the front wheels 85 we have provided the following means.

On the shafts 83 preferably near the upper ends thereof are parallel forwardly extending arms 103 which are pivoted and connected by a connecting rod 104.

120 On one of the arms 103 is formed a toothed sector 105 which is arranged in mesh with a worm 106 on a shaft 107 mounted in suitable bearings on the frame of the machine and having at its end a crank handle 108.

125 By manipulating the handle 108 the shafts 83 may be rocked or rotated for steering the 130

wheels 85 mounted on the spindles 84 at the lower ends of said shafts.

For the propulsion of our improved earth handling machine during the ordinary operation thereof, we provide a cable 109 which is designed to be firmly fixed at its ends. Each end of the cable 109 is designed to be yieldingly held by some suitable device such, for instance, as a sleeve 110 having at one end a cap 111 on which is a hook 112. On the other end of the sleeve 110 is a removable cap 113. Slidably mounted in the cap 113 and having the greater portion of its length received within the sleeve 110, is a rod 115. On one end of the rod 115 is a hook 114 secured to the cable 109. On the other end of the rod 115 within the sleeve 110 is adjustably mounted a nut 116.

Between the nut 116 and the cap 113 is a coil spring 117.

Suitably mounted at the forward part of the machine is a transverse shaft 118 on which is a sheave wheel 119. On the outer end of the shaft 118 is a drum 120 which is used for carrying spare cable or for carrying the cable 109 when it is not in use. On the shaft 118 on opposite sides of the wheel 119 are gears 121.

Suitably mounted on the frame of the machine rearwardly of the shaft 118 is a transverse shaft 122. On the shaft 122 is a sleeve 123. On the outer end of the sleeve 123 are mounted wide gears 124 which mesh with the respective gears 121, as illustrated more particularly in Fig. 3. The sleeve 123 also has spaced beveled gears 125 mounted between the gears 124, as shown in Fig. 3. The shaft 24, hereinbefore referred to, is connected by means of a selective speed transmission gear 126 of any ordinary construction, which does not in itself form a part of our invention, with a shaft 127 on which is a beveled gear 128.

For sliding the sleeve 123 and thereby selectively moving the respective beveled gears 125 into mesh with the beveled gear 128, the following means has been provided.

Pivoted between its ends on a bracket 129 is a bell crank lever 130, one end of which is operatively connected with the sleeve 123 at 131, for sliding said sleeve longitudinally on the shaft 122 while permitting free rotation of said sleeve.

Pivoted to the other end of the bell crank lever is a rearwardly extending link 132, shown in Figs. 2, 3 and 4. The link 132 is pivoted at its rear end to a controlling lever 133 mounted on the frame of the machine.

It will be seen that by manipulation of the lever 133 the sleeve 123 can be moved for bringing either of the gears 125 into mesh with the gear 128 for thereby imparting rotation to the shaft 122 in either direction.

65 The gears 124 are fixed on the sleeve 123

and slide with it, but they have wider faces than the gears 121 and hence are always in mesh with the gears 121, so that the gears 121, and shaft 118, and sheave wheel 119 may be rotated in either direction.

70

The cable 109 is threaded through suitable guides on the machine and is wound on the drum 119 when the machine is to be operated by means of the cable.

On the hubs of the wheels 85 are sprocket gears 134, which are respectively in alignment with sprocket gears 135 on the ends of the shaft 122. On each pair of gears 134 and 135 is a sprocket chain 136. On the shaft 122 is an ordinary band brake 137 connected by means of a link 138 with a controlling lever 139.

75

Connected with the transmission gearing 126 is a centrally pivoted lever 140 which is pivoted to a link or rod 141 extending rearwardly in the machine and connected with a controlling lever 142.

80

Mounted at the rear part of the machine is a scraper blade 143, shown in Figs. 1 and 2. The scraper blade is supported upon a frame having a semi-circular member 144 provided with teeth on its upper surface. Suitably mounted above the plate or platform 86 is a hand-wheel 145 connected with a rod or shaft 146. The rod or shaft 146 is connected by a universal joint 147 with a shaft 148 on which is a beveled gear 149 in mesh with the teeth on the upper surface of the frame member 144.

90

Suitably mounted on frame members are 100 large hand-wheels 150 on shafts 151. On the shafts 151 are worms 152 which mesh with worm gears 153 rotatably mounted on shafts 154. On each shaft 154 is a friction disk clutch member 154^a. Each worm gear 153 has a smooth face adapted to engage the face of the disk 154^a, and the said worm gears 153 are yieldingly held in engagement with the disk 154^a by means of coil springs 154^b to permit some slippage. By means of nuts 154^c the tension of said springs may be varied. This friction device for attaching the worm 153 to the shaft 154 is a safety device to prevent breaking the lifting arms or shafts 154 when the scraper blade 145 strikes large boulders or other obstructions.

105

Each of the shafts 154 has a crank 155 operatively connected with a link 156. The links 156 are connected with the opposite sides of the frame which supports the 110 scraper.

115

Suitably supported near the engine 14 is a fuel tank 157.

In the practical operation of our improved earth handling machine when it is 125 desired to use the machine for grading purposes, the cable is stretched and anchored at its ends after having been threaded through the machine and wound over the sheave wheel 119.

130

The machine can then be drawn forwardly by starting the engine and throwing the clutch members 25 and 23 into gear by means of the lever 30. The lever 133 is 5 then operated for throwing the gear 128 into mesh with the proper gear 125 for advancing the machine. The crank 74 is operated for moving the earth cutting tool to proper position adjacent to the endless carrier, and the forward end of the endless carrier and the earth cutting tool are lowered by means of the hand-wheel 59 for regulating 10 the depth of the cut which it is desired to make.

15 It will be noted that when the machine advances the earth is not only cut by the earth cutting tool, but the plate or blade 64 is of such shape and so curved as to elevate the earth and discharge it on the forward portion of the endless carrier.

The plate 80 assists in determining when the dirt is loaded to the proper height on the endless carrier. When the dirt is pulled up to the plate 80 the endless carrier is 25 thrown into gear by means of the lever 36 and the lever 43 for moving the upper stretch of the endless carrier rearwardly a short distance.

When the endless carrier has been loaded 30 the machine can be moved to another place, and the dirt, if desired, may be discharged at the rear end of the endless carrier and as the machine advances the scraper blade 143 will smooth and level the dirt discharged 35 from the endless carrier, or shove the earth discharged from the conveyer off over the edge of a fill or grade when it is desired to widen the same or to fill a ditch at the side of a roadway. It will be noted that the endless carrier thus forms a carrier and also a 40 load holding means.

On account of the manner in which the gears 52 are connected with each other and with the source of power, every other roller 45 under the endless belt 20 is operated, so that there is no danger of any slippage of the endless belt 20 on the rollers.

If it is desired to discharge the dirt at the forward end of the endless conveyer this 50 can be done by reversing the direction of movement of the endless conveyer by shifting the friction wheel 31 on the shaft 24 for causing the upper stretch of the endless conveyer to travel forwardly in the machine.

55 We consider this, in connection with the other features of the machine hereinbefore described, to be one of the important features of our invention. For instance, if it is desired to fill a ditch or depression, the 60 machine can be moved forwardly until the large wheels 85 drop over the edge of the ditch. The frame of the endless conveyer will then rest on the ground and it will be noted that the frame is so constructed, as shown in Figs. 5 and 8, with the rigid bot-

tom 160, (shown in Fig. 8) that it may rest on the ground at the edge of the ditch without interfering with the movement of the endless carrier. The dirt can then be discharged from the endless conveyer immediately 70 into the ditch. In this connection attention is called to the advantage of the construction of the machine whereby the earth cutting device is mounted on a frame which is raised and lowered with the forward part of the endless conveyer, and is also adjustable with relation to such frame and with relation to the forward end of the endless conveyer, so that when dirt is being discharged at the forward end of the endless 75 conveyer, the earth cutting device may be raised to be out of the way of the discharging load. It may be noted here also that on account of the construction hereinbefore mentioned, the guide plate 80 is raised out 80 of the way when the earth cutting device is moved away from the forward end of the endless conveyer.

85 After the load has been discharged, the sheave wheel can be thrown into gear for 90 pulling the machine away from the ditch. This can be done because the pull is on the cable and the machine is not operated by the movement of the large front wheels. It will be seen that no such operation could be 95 performed with an ordinary tractor. We consider this combination of the digger located substantially below the shaft on which the supporting wheels are mounted, with a sheave wheel and cable, an important 100 one. Where it is desired to make a cut along the ground for a considerable distance to a uniform depth, it is necessary to locate the cutting member substantially below one of the axles. If the cutting member 105 is located rearwardly or forwardly from the axle, then the operation of the cutting member serves to increase any unevenness in the ground, and does not result in cutting to an even depth. For instance, if the cutter is located ahead of the axle and the wheels on the axle drop into a low place, it will be seen that the cutter would then cut greater than the required depth, while if the wheels went over an elevation the cutter 110 would not cut to the required depth; so it is desirable to locate the cutter substantially below the axle.

115 Where the cutter is located below the axle, it will be seen that with an ordinary 120 tractor it would be impossible to move the machine to the edge of the ditch or hole for discharging at that end of the conveyer where the cutter is located, but with the sheave wheel and cable construction the machine can be moved for discharging into 125 a ditch in the manner hereinbefore described.

125 It will be seen that the scraper blade 143 is greater in length than the total width of

the machine at its widest part, so that if it is desired to cut off a part of a side hill this can be done by pulling the machine along side the hill with the scraper blade 5 so arranged that it projects beyond the machine for cutting off a portion of the hill. This operation can be done while at the same time picking up loose dirt that may have been cut off at a previous operation 10 and loading such loose dirt.

It may be noted that both the front and rear wheels are steerable so that the machine can be operated for making any turn desired.

It may be noted also that on account of 15 the last mentioned feature of construction, the rear end of the machine may be caused to travel in a path at one side of the center of the path of travel of the front part of the machine so as to make any desired width 20 of cut into a bank or ridge, or shove the earth discharged from the conveyer over the edge of a fill for the purpose of widening or filling a ditch at the road side.

The scraper blade 143 can be adjusted by 25 raising and lowering either end or by raising and lowering the entire scraper blade and by swinging the scraper blade so that its cutting edge is arranged at different angles with relation to the path of travel of 30 the machine for surfacing a road or the like in different ways.

It will be noted that when it is desired to move the machine from one job to another, the cable may be taken off the sheave 35 wheel and wound on the drum 118 and by putting chains 136 on the sprockets 134 and 135 the machine may be carried over the ground under its own power, as an ordinary tractor. These chains are removed and not 40 used when the cable is used. It will be understood that when the chains 136 are in use, the front wheels are not steered and the machine is steered by the operation of the rear supporting wheel.

45 The machine is primarily, however, intended to be operated with the cable when used for heavy work.

It will be seen that it can be used for cutting down ridges or banks, for grading, for 50 loading and carrying dirt, and can be used for cutting off a ridge and depositing the dirt and leveling it. It can be used for simultaneously cutting down a bank and picking up and loading the dirt that was 55 loosened by a former cut.

The machine ordinarily requires only three men for its operation.

Some changes may be made in the construction and arrangement of the various 60 parts of the machine without departing from the essential spirit and purpose of our invention, and it is our intention to cover by our claims any modified forms of structure or use of mechanical equivalents which

may be reasonably included within their scope.

We claim as our invention.

1. In a device of the class described, a frame mounted on wheels, an endless conveyer frame tiltably supported on said frame, an endless conveyer on said second frame, a load supply device adjacent to one end of said conveyer, means for mounting said load supply device on said conveyer frame for permitting adjustment of the load supply device with relation to the endless conveyer, a plate mounted above one end of said conveyer adjacent to said load supply means and operatively connected with said load supply means.

2. In an earth handling machine, a frame mounted on wheels, an endless conveyer adapted to move a load and to be thrown out of gear for retaining said load, means for operating the endless conveyer, including mechanism for throwing the conveyer into or out of gear, a load supplying device arranged adjacent to one end of said endless conveyer, and an adjustable scraper arranged adjacent to the other end of said conveyer adapted to act on material discharged from other end of said conveyer.

3. In an earth handling machine, a frame mounted on wheels, a conveyer frame tiltably mounted on said first frame, an earth cutting and elevating device mounted to be moved with said conveyer frame, and adapted to be adjusted with relation thereto, means for raising and lowering the ends of said conveyer frame, together with said earth cutting and elevating means for varying the depth of cut of the latter, a conveyer on said conveyer frame, means for operating said conveyer and throwing it into or out of gear, whereby the conveyer may be used to move a load or to retain the load while the machine is being moved from one location to another, and a scraper adjacent to the end of said conveyer opposite said earth cutting means adapted to act on material discharged from the last mentioned end of said conveyer.

4. In an earth handling machine, the combination of a frame mounted on front and rear steerable wheels, with a load carrier on said frame, an earth cutting and elevating device adjacent to said load carrier and near the front end of the machine, an earth cutting device near the rear end of the machine arranged to project laterally beyond the machine in certain positions of the machine and said first earth cutting device.

5. In an earth handling machine, the combination of a frame mounted on wheels, an endless carrier on said frame adapted to retain a load and to be operated at will for discharging said load at either end, an earth

cutting and elevating means adjacent to the forward end of said endless carrier, a scraper mounted on said frame rearwardly of said carrier adapted to smooth and level 5 dirt or the like discharged from the rear end of said carrier.

6. In a machine of the class described, a frame mounted on wheels, mechanism for cutting and loading dirt or the like, mechanism for retaining said dirt, adapted to be 10 operated at will for discharging said dirt, and mechanism for smoothing and leveling said discharged dirt.

7. In an earth handling machine, a frame 15 mounted on wheels, an endless conveyer, a load supplying device arranged adjacent to one end of said conveyer, and an adjustable cutting blade arranged adjacent to the other end of said conveyer adapted to cut earth at 20 the side of the machine for cutting away banks or hill-sides.

8. In an earth handling machine, a frame mounted on wheels, a conveyer thereon, a load supplying means adjacent to one end 25 of said conveyer, a scraper blade adjacent to the other end of said conveyer, means for adjustably supporting and for raising and lowering the ends of said scraper blade, said means including slippage devices.

30 9. In a device of the class described, a frame mounted on wheels, a load carrying device thereon adapted to discharge its

load at one end, a scraper mounted near one end of said load carrying means, means for raising and lowering and for supporting the ends of said scraper blade, said means including 35 friction devices for permitting the slippage when the blade strikes an obstruction for permitting the blade to raise and clear such obstruction.

10. In a device of the class described, the 40 combination of a frame having supporting wheels near one end, and a supporting wheel near the other end, an endless conveyer adapted to discharge near said one end, a digging device arranged substantially in line 45 between said first described wheels for digging dirt or the like for loading said conveyer, with a sheave wheel, a cable on said sheave wheel, and means for causing the entire machine to travel along said cable. 50

11. In a machine of the class described, a frame, supporting wheels near the opposite ends of the frame, an endless conveyer, a digger for digging dirt and loading said conveyer, arranged substantially between the 55 wheels at one end of the frame, a cable, and means on said machine for engaging the cable and causing the machine to travel along the cable.

Des Moines, Iowa, January 21, 1918.
